UNITED STATES PATENT OFFICE.

JOHN LEWIS TANDY, OF HORTON, KANSAS.

CABINET.

SPECIFICATION forming part of Letters Patent No. 759,770, dated May 10, 1904.

Application filed May 25, 1903. Serial No. 158,644. (No model.)

To all whom it may concern:

Be it known that I, JOHN LEWIS TANDY, a citizen of the United States, residing at Horton, in the county of Brown and State of Kansas, 5 have invented certain new and useful Improvements in Cabinets; and I do hereby declare the following to be a full, clear, and exact description of the invention, such as will enable others skilled in the art to which it appertains to 10 make and use the same.

This invention relates to a new and useful cabinet composed of a series of detachable sections for holding, classifying, and displaying mounted window-shades, rollers, curtain- 15 rods, poles, and similar articles; and its object, among other things, is to provide a convenient, inexpensive, portable cabinet for carrying, classifying, and displaying a stock of window-shades mounted on rollers and to 20 protect the same from dust, flies, &c., and a cabinet that can be made any desired size in a moment's time by attaching or detaching sections of which it is formed.

To these ends the invention consists in the 25 novel construction and combination of parts hereinafter more fully described and claimed, and illustrated in the accompanying drawings, showing the preferred form of my invention, and in which—

30 Figure 1 represents a perspective view of a cabinet embodying my invention. Fig. 2 represents a top view of a side portion of one of the "sections." Fig. 3 is a vertical section taken through the side portions of one of the 35 sections and also shows the corresponding rear end sash or portion having downwardly-diverging pins interlocked with said side portions. Fig. 4 is a vertical section of side portions of contiguous sections, the portion of 40 the upper section being disposed horizontally preliminary to being swung to the upright position in which it is to be interlocked with the one below. Fig. 5 is a similar section of said sections after one is placed vertically upon 45 the other and they are interlocked together.

Referring to the drawings forming a part of this specification, and on which like letters of reference indicate corresponding parts in the different views, Fig. 1 is a cabinet composed of a series of sections A, each of which,

with bottom B and top C, is complete within itself. A is a rectangular section or frame of any desired size formed of two sides D and back end E, which is detachably fastened at each end to sides D by means of diverging 55 pins or fasteners F. This permits the section A to be knocked down quickly for convenience of attaching to other sections, as seen in Fig. 4 and hereinafter described, and also for convenience in handling and shipping. The 60 front end is left open preferably for the convenience of putting in and taking out the shades, &c.; but it is obvious that it may be closed by a door, &c., or when desired an ordinary mounted shade may be hung at the top of 65 the opening in brackets J and raised or lowered at will. The front and back ends of sash D' or sides D of section A are detachably connected at their top sides reasonably close to their ends by bars or cross-pieces a, being dove- 70 tailed into said sash, as shown in Fig. 2. The space between the sides D along the bar a, both front and back, is divided at regular intervals by partition bars or preferably rounds b into any desired number of compartments 75 for the reception and classification of shades, &c., as shown in Fig. 1. Cross-bars a and the bottom B are provided with holes to receive the partitions b. These partitions, like other parts of the cabinet, are made detachable for the convenience of knocking down and setting up. The bottom B may be made solid or simply of two cross-bars immediately under bars a, either of which may be provided with casters H. 80

The top C is a removable frame or covering for the cabinet and may be set aside while attaching or detaching sections. 85

The sides D and end E are preferably formed of a sash D', (similar to a one-light window-sash,) filled with glass, pasteboard, wood board, veneering, cloth, &c., though it is evident that they may be made of any suitable material and desired form.

The sections A are preferably attached to 95 each other by a modified form of a hook and eye, as illustrated in Fig. 4, in which G is the hook, and G' is the eye. The eye G' is sunk in the top of the sides D of the sections or in the top part of the sash D, one near each end, 100

while the hook G is projected at similar points from the bottom of the sash D'. To attach the said sections, the side D or sash D' must be inclined to the inside until the hook G is 5 in a position to interlock with the eye G'. Then the sash D' is raised to a vertical position and the attachment is securely made. After the same process on the other side the end E is placed in position between the sides D at rear 10 end of same, as shown in Fig. 3. Then the section A is securely attached to the one below it. Cross-bars a, partitions b, and top C are then placed in position. I do not confine myself to this mode of attachment, however, as there 15 are other means of accomplishing the same result.

While I have shown the cabinet with a series of but four sections, it is obvious that it may be composed of any number of sections.

20 In the foregoing description I have shown the preferred form of my invention; but I do not limit myself thereto, as I am aware that modifications may be made therein without departing from the spirit or sacrificing the 25 advantages thereof, and I therefore reserve the right to make such changes as fairly fall within the scope of my invention.

Having thus fully described my invention, what I therefore claim as new, and desire to 30 secure by Letters Patent thereon, is—

1. A sectional cabinet, comprising a bottom, a "section" mounted thereon, and comprising sides, an end connecting the same, cross-bars also connecting the sides, and partition-rounds 35 projecting from the cross-bars, in combination with one or more like "sections" superposed with respect to and detachably connected to the "section" first named, and a top detachably surmounting the topmost "section."

40 2. In a cabinet, a section comprising substantially parallel sides, an end connecting the same, cross-bars also connecting the sides, and partition-rounds projecting from the cross-bars.

45 3. In a cabinet, a section comprising substantially vertical sides, a rear end portion detachably connected to said sides, cross-bars detachably connected at their ends with the sides,

one or more partition bars or rounds depending from each cross-bar, and a portion resting 50 detachably upon said section and end portion.

4. A cabinet, comprising a bottom, substantially parallel sides detachably secured thereto, a rear end detachably connected to the sides, cross-bars detachably connecting the sides, one 55 or more substantially vertical partition bars or rounds suitably supported and disposed between the bottom and said cross-bars, and a top detachably mounted upon the sides and overlying said cross-bars. 60

5. A cabinet, comprising a bottom having eyes, substantially parallel sides resting upon the bottom and having hooks detachably engaging said eyes, a rear end detachably connected to the sides, cross-bars detachably connecting the sides, one or more substantially vertical partition bars or rounds suitably supported and disposed between the bottom and said cross-bars, and a top detachably mounted upon the sides and overlying said cross-bars. 70

6. A cabinet, comprising a bottom, substantially parallel sides detachably secured thereto, a rear end detachably connected to the sides, cross-bars connected with the sides, one or more substantially vertical partition bars or 75 rounds suitably supported and disposed between the bottom and said cross-bars, and a top detachably mounted upon the sides and overlying said cross-bars.

7. A cabinet, comprising a bottom having 80 eyes, substantially parallel sides resting upon the bottom and having hooks detachably engaging said eyes, a rear end having downwardly-diverging pins interlocked with the sides, cross-bars having connections with the 85 sides, one or more substantially vertical partition bars or rounds suitably supported and disposed between the bottom and said cross-bars, and a top detachably mounted upon the sides and overlying the cross-bars. 90

In testimony whereof I affix my signature in the presence of two witnesses.

JOHN LEWIS TANDY.
